KNITTING METHOD AND MACHINE

Paul W. Bristow, Laconia, N. H., assignor to
 Standard-Trump Bros. Machine Company,
 Laconia, N. H., a corporation of Delaware

Application May 8, 1935, Serial No. 20,312

11 Claims. (Cl. 66—108)

This invention relates to a knitting method and machine and has particular reference to the production of selective normal and reverse plating by selective manipulation of special sinkers 5 or elements associated therewith.

As is well known at the present time, the character of plating produced in loops of a knitted fabric when two yarns are fed in predetermined relationship to needles may be varied by selective 10 manipulations of specially designed sinkers or elements associated therewith as the stitches are being drawn.

The character of action of the sinkers or other elements upon the yarns may vary depending 15 upon the character of the associated elements, the feed of the yarns, etc., but in all cases of such reverse plating there is involved some variation in movement of the sinkers or associated elements, the variations being attained through 20 suitable controlling mechanism.

In an application filed by Harold E. Houseman on January 25, 1935, Serial No. 3,376, there is disclosed an improved controlling mechanism whereby elaborate patterning may be secured. 25 through selective plating and reverse plating, although the mechanism involved is of a quite simple character. In said application the controlling elements are shown as applied to a sinker reverse plating mechanism in which specially 30 formed sinkers are provided and means associated therewith are used to project the sinkers inwardly prematurely at predetermined times to cause the loops to be drawn either in front of or behind the nibs of the sinkers to thereby effect either normal or reverse plating. In most 35 mechanisms heretofore used for producing sinker reverse plating, the sinkers or elements associated individually therewith are provided with a number of butts. Unless such number of butts 40 is objectionably increased, however, to an extent taking up an undue amount of space and giving rise to objectionable lateral thrusts, there is a definite limit to the character of patterns which may be produced. In accordance with said application, there is provided a selecting method 45 and means for securing the varying operations of sinkers or elements associated therewith at desired times, which method and means are adapted for the production of very elaborate patterns 50 involving numerous variations in selection.

In those controlling arrangements which utilize butts on sinkers or other elements associated with sinkers, the patterns produced were generally and almost necessarily of a quite simple 55 character, because of the limited variations per-

mitted by the controlling mechanism. Since a normal or reverse plating condition of the yarns in such simple patterns extended over a considerable number of successive wales, no difficulty was generally experienced in securing the 5 changes from normal to reverse plating, and vice versa, at definite needles. The controlling arrangement of the H. E. Houseman application just referred to, however, permits a wide range of selectivity and consequently very elaborate 10 patterns involving, for example, quite narrow vertical stripes, blocks made of reverse plated spots instead of being solid, etc., to produce which patterns it is necessary that the yarns be continuously twisted back and forth so that reverse 15 plating may occur over but one or very few successive wales, followed by a similar quite short extent of normal plating, to be again followed by reverse plating. It is one object of the present invention to insure that such continuous reversal 20 of the yarn positions may be effected without the condition of the yarns in a sinker wale affecting the yarns in an adjacent needle or vice versa; in other words, so as to avoid streak-offs.

It is known to impart to the sinkers or other 25 elements which are controlling reversal of the yarns a slight outward movement just as the yarns are being drawn over the sinkers to aid to some extent in the reversal of the yarns but primarily to secure equalization of the reverse and 30 normal plated loops to prevent puckering of the fabric. In accordance with the present invention, provision is made for securing such outward movements of the sinkers or other elements 35 at precisely the right times so as to effect the production of very clean reverse plating. Extreme precision is very necessary; in fact, it has been found that the slightest adjustment of the other elements with a fixed retracting cam would produce a disturbance which would prevent the 40 formation of clean reverse plating, as, for example, a slight raising or lowering of the needle cylinder to accommodate heavier or lighter yarns, whereby the level of sinkers was changed, or a change in the adjustment of a sinker cap bumper 45 screw made for any reason. In accordance with the present invention, accordingly, provision is made for finely adjusting the cam which controls these outward sinker movements to compensate 50 for any conditions which might arise and secure the proper sinker movements to produce clean reverse plating.

Another object of the present invention relates 55 to the proper control of the fabric loops when reverse plating is taking place. After reverse

- plated loops have been drawn over the backs of the sinker nibs, they are caused to slip over to the front of them when the needles ride up the end cam. Frequently, especially if the fabric is loose, when they slip forward they will pull the loops of the previous course, which are in the sinker throats, out of the throats so that the fabric gets above the sinkers and therefore out of control. This action is avoided in accordance with the present invention by a second depression of the needles after they have moved up the end cam to a point just below the sinker nibs whereby the loops are carried downward and at the same time a supplementary sinker cam backs the sinkers away as the needles descend and then permits them to move in as the needles reach their low point to cause the throats of the sinkers to reengage any loops which were previously lost.
- 20 These and other objects of the invention, particularly relating to details of construction and manipulations, will be apparent from the following description read in conjunction with the accompanying drawings, in which:
- 25 Fig. 1 is a diagrammatic vertical section through a needle cylinder and associated parts illustrating certain elements used in conjunction with the present invention;
- Fig. 2 is a diagrammatic perspective view indicating the production of normal and reverse plating and particularly movements of sinkers during such action;
- Fig. 3 is an inside development of various needle, jack, sinker and other associated cams;
- 30 Fig. 4 is a diagrammatic plan view, partly in section, showing certain cams and cam controlling means;
- Fig. 5 is a horizontal section showing controlling devices for effecting selection;
- 40 Fig. 6 is a fragmentary elevation showing the same subject matter as Fig. 5;
- Figs. 7 and 8 are detail views of sinker controlling cam members; and
- Fig. 9 is an enlarged diagrammatic perspective view showing certain specific events in reverse plating.
- The knitting machine which is specifically illustrated for the purpose of showing the invention is, in general, of conventional character and only so much of the machine is illustrated as is necessary for a clear understanding of the invention. The machine comprises an elongated rotary needle cylinder 2 rotated through the medium of a ring gear 4, which cylinder is provided with the usual slots 6 for the reception of needles, and other associated parts. The needles are of the usual latch type and are provided with butts 10 and shoulders 12 located, as illustrated, above the butts. The cylinder is vertically adjustable for the accommodation of different yarns or for stitch variation by mechanism of the type shown in H. E. Houseman Patent No. 1,927,568, which mechanism comprises vertically movable pins 5 on which ring gear 4 rests.
- 65 Located in the needle slots above the shoulders 12 are jack guides 14 held normally in an upper position by spring bands 17 above and below small projections indicated at 16. The projections 16 are so formed as to tend to latch the jack guides in upper position, but when sufficient force is applied, tend to cam the lower of the spring bands outwardly to permit the jack guides to move down. Each of the jack guides is provided with a butt 18 designed to be acted upon by suitable cams as described hereafter. In

order to provide for the proper guidance of jacks 20, each of the jack guides is provided with upper and lower arms, respectively designated at 19 and 15, designed to embrace the inner end of a jack 20 which is guided within a slot in sinker dial 28 aligned with a corresponding needle slot. Each of the jacks 20 is provided with an upwardly extending arm 23 having a laterally turned upper end designed to engage a downward projection 36 formed on an adjacent sinker. The corresponding sinkers are, of course, slightly displaced circumferentially from their operating jacks in as much as they must pass between the needles, and the turned ends of the arms 23 insure proper cooperation between the jacks and sinkers. Each of the jacks is, furthermore, provided with an upwardly extending butt 22 and one or more butts 83, only one of which is shown in this case. A plurality of butts may be provided if more elaborate control is desired, as disclosed in the 20 Harold E. Houseman application referred to above. The butts 22 are arranged to be acted upon by cams at proper times to effect inward and outward movements of the jacks while the butt 83 is arranged to be acted upon to effect 25 inward movements thereof.

The sinker dial 28 is surmounted by the usual sinker cap 24 which carries sinker operating cams, described below, and is arranged for limited circumferential movement in the usual 30 fashion. Besides the cams designed to operate on the butts 37 of the sinkers, this sinker cap also carries cams 25, 53 and 41 arranged to operate at suitable times upon the butts 22 of the jacks 20.

The sinker dial 28, which is slotted on its top for the sinkers and on its bottom for the jacks, rests on the cylinder walls. Four segmental clamp rings 26 pull the dial down against the cylinder walls and also form a fulcrum for the 40 rocking of the jacks. The rings 26 are drawn downwardly by the clamps 27, two of which are provided for each segmental ring 26, the clamps being connected to the rings by screws 29 and engaging ledges formed on the cylinder walls. 45

Each sinker 30 is provided with an upper arm 32 having a sloping upper surface providing a ledge over which stitches are drawn and also a lower arm 34 guided in the cylinder top 35. Each of the sinkers is provided with a nose or nib 31 50 behind which there is a sloping edge 33 on which stitches are drawn to effect reverse plating. The sinkers are provided with the usual butts 37 acted upon by cams designed to impart to them their usual movements. The premature movements to effect reverse plating in the present instance are imparted by cams acting upon the butts 83 of jacks 20. Cams 43, 45 and 47 are provided to act upon the sinkers. Cams 43 and 47 effect the proper sinker movements during rotary knitting and reciprocation in a forward direction, while cams 43 and 45 effect corresponding movements during knitting in a reverse direction. A cam 41 is provided secured to the sinker cap to act upon the jack butts 22 and hold the jacks 20 inwardly 60 at proper times to insure against their being thrown outward by centrifugal force. 65

The cam designated generally as 43 is shown in detail in Figs. 7 and 8. This cam comprises two separate elements as shown in the figures. One 70 of these, shown in Fig. 8, provides a cam surface 171 designed to engage the sinker butts to move the sinkers outwardly and thereafter permit the sinkers to move inwardly as they pass the surface 179. The other element 170 forms a continuation 75

of this cam and provides an outward cam surface 171 designed to give to the sinkers which are effecting reverse plating a slight outward reverse movement to secure proper control of the yarns 5 as indicated below. The two cam portions are secured together by a clamp screw 174, a pin 172 carried by the cam section 170 being guided in a slot in the extension 49 of the cam member 171. By reason of the pin and slot connection between 10 the parts, a fine circumferential adjustment of the cam 171 relative to the fixed cam 177 is provided.

Inasmuch as the usual cam 43 is cut away at its trailing end as indicated at 179 in order to permit premature inward sinker movements, the spring band 39 would normally tend to move the sinkers inwardly even though they were not acted upon by the jacks 20 and were not intended to move inwardly until acted upon by cam 47. In 20 order to avoid such premature inward movement under spring band action, there are preferably inserted in the sinker slots special band holding bits, one for each sinker, which are adapted to be acted on by a cam indicated at 49 to hold the 25 spring bands outwardly until such time as the sinkers which are to produce normal plating are moved inwardly by cam 47. Such band holding bits are well known and are not described herein, since they form no essential part of the present 30 controlling means. They are shown, for example, in the patent to Pons No. 1,821,848, dated September 1, 1931. Cam 49, which controls them, is formed as an upper portion of the cam 43 and is not engaged by the sinker butts but acts upon 35 the butts of the band holding bits which are longer than the butts of the sinkers 30.

Located in the needle slots below the needles are intermediate needle jacks 38 provided with butts 40, while below these intermediate jacks are 40 located lower tilting jacks 42 whose inner edges are so formed as to provide pivots 44 about which as horizontal axes the jacks may rock. At their lower ends the jacks 42 are provided with shoulders 46 adapted to engage cams, as will be hereafter more fully pointed out. The jacks are also provided below their pivots with butts 48 which may be selectively arranged for the purpose of producing patterns. The jacks may be supplied, for example, containing a full complement of butts which may be selectively broken out in order 50 to provide the necessary setup for a desired pattern.

Referring to Fig. 3, there is disclosed therein the layout of cams arranged to act upon the needles, 55 jacks 20, sinkers 30 and the butts of jack guides 14, and the intermediate and lower jacks 38 and 42. The needle stitch cams are of the usual variety and comprise the upper center cam 53 and the usual stitch drawing cams 52 and 54, the former of which serves to draw the needles downwardly during rotary knitting.

Cooperating with the lower jacks there are an upper cam 56 designed to rock the lower ends of the jacks outwardly and a series of lower cams 60 60 and 62 designed to rock the lower ends of the jacks inwardly. All of these cams are formed as levers and will be referred to hereafter. The lowermost of the cams designed to rock the jacks inwardly is designated differently from the others, 65 since it performs a somewhat different function. In advance of the cams 60 there is located a fixed cam 58 which is designed to engage the shoulders 46 on the lower jacks and cause them to rise to a predetermined level before they reach the location of the cams 60. This action insures a 70

proper vertical alignment between the butts on the jacks and the various corresponding cams 60. There is also provided, in a position following the cams 60, a cam 66 having an upward slope 64 on which the shoulder 46 of such of the jacks 42 as 5 have their lower ends extending outwardly may ride, whereby such jacks will be raised. A slope 68 provided on the cam 66 serves to rock the lower ends of the jacks inwardly and thus disengage them from the top level of the cam 66. A guard 10 cam 70 is provided to prevent possibility of damage to the jacks during reciprocation and limit their downward movements.

A cam 72 is provided designed to engage the butts 18 of raised jack guides 14 so as to depress 15 all of the jack guides at its position. This is to prepare the jack guides for a subsequent selection.

Cams 74 and 76 are respectively designed to raise and lower needles by engagement with their 20 butts 10 for purposes which will hereafter become apparent. The lowering action of cam 76 is continued by the usual guard cam 78. A ring of cams indicated at 81 serves to maintain the intermediate jacks within the needle slots. A cam face 25 80 on the lower portion of this series is adapted to engage the butts 40 of the intermediate jacks to lower them and with them the lower jacks 42.

A cam 82 is adjustably mounted by a screw and slot connection, indicated at 83', upon a lever 30 84 and is arranged to act upon the butts 83 of the horizontal sliding jacks 20. A cam 86 is provided to raise the needles to a desired level. It may be noted that the loops on needles which may be raised due to selection clear the latches 35 as jacks pass up cam 64, while the loops on needles which are not raised clear the latches thereof at cam 54.

Besides the cam mentioned above, there are provided a cam 51 arranged to raise jack guides 40 14 and a cam 53 carried by the sinker cap and arranged to engage butts 22 and move jacks outwardly. Both of these cams are used to avoid 45 improper actions of the elements during reciprocation, and their functions will be brought out hereafter. Other cams are provided for the purpose of producing, for example, gusset toes, but need not be described since they have no direct relationship to the present invention.

A cam 87 is provided in the position indicated 50 in Fig. 3 to move the needles downwardly after they have been raised by the cam 86. This cam 87 is carried by a bell crank 180. There is also provided a cam 190 for engaging the sinker butts and moving the sinkers outwardly as needles 55 move down under the action of cam 87.

The layout of cams having been described, reference will now be made to their controlling means. The lever 84 which carries the cam 82 is provided with an arm 90 in which is mounted 60 an adjustable follower screw 93 arranged to be engaged by a cam 94 pivoted at 98, which cam is designed to move it against the action of spring 92 so as to cause the cam 82 to move inwardly to engage the butts 83 of the jacks 20. Movements 65 of the cam 94 are controlled by a link connection 104 to one of a series of nested shafts indicated at 105 in Fig. 6. These shafts are provided at their lower ends with follower arms engaging suitable cams on the main pattern drum 111. The 70 control in this respect is similar to that described in the H. E. Houseman application referred to. A spring 102 normally urges the cam 94 in a counter-clockwise direction to free the follower 75 93 and permit the cam 82 to withdraw outwardly.

The bell crank 180 which carries the cam 87 is connected by a link 182 to the cam 94, which connection is made in such fashion that the cam 87 is withdrawn outwardly when the cam 82 is 5 permitted to move outwardly.

A cam 190 arranged to engage the sinker butts is pivoted at 191 to the sinker cap and is provided with a pin connection 192 to a lever 194 pivoted at 195 to the sinker cap and connected by a link 10 196 to the cam 94. The link 196 is in the form of a wire extending through an eye 200 carried by the cam 94 and is provided with a head 198 arranged to be engaged by the eye. From these connections it will be obvious that the cam 190 15 is rocked outwardly so as to produce a retraction of the sinkers whenever the cam 82 moves inwardly. When the cam 82 is permitted to move outwardly, the sinkers under the action of the spring band 39 will restore the cam 190 to its inner 20 position.

The needle circle is approximately indicated at 114 in Fig. 4. The cams 74 and 76 are moved radially together and cam 72 is also subject to controlled radial movements through the medium 25 of levers 136 and 138 controlled by cams 140 on the main cam drum 111. The controlling arrangements are described in detail in the H. E. Houseman application mentioned above.

Control of the cams 60, which are formed as 30 levers pivoted at 141, is effected by the action upon tails thereof of tricks carried by a trick wheel 142. These tricks, which are receivable in slots in the trick wheel in the usual fashion, are provided with butts which may be selectively arranged to produce the desired control of the 35 cams 60. The trick wheel 142 is stepped about intermittently by the action on a ratchet 144 carried thereby of a pawl 146 which is oscillated through the medium of a link 148 by the lever 40 150 which rides upon lugs carried by the links of a pattern chain 152 which is advanced one step upon each revolution of the needle cylinder. By a suitable setup of the lugs on the pattern 45 chain, the trick wheel may be advanced upon each revolution of the needle cylinder or at less frequent intervals. A guard 154 is provided for interrupting the advance of the trick wheel and for securing a setup thereof at the completion of a stocking, this being effected as described in the 50 application of Stanley R. Shelmire, Ser. No. 623-057, filed July 18, 1932.

The cam 56 is formed on a lever which has a functionally integral, adjustable extension 156 55 connected by a link to a lever 158 which is secured to one of a series of vertical nested shafts whose lower ends carry cams acted upon by cams on the pattern drum 111.

If desired, the series of cams 60 may operate in a plurality of sets. In the machine illustrated, for example, there are three such sets. By reason of such arrangement, there is made a convenient provision for the formation in a single stocking of three quite different independent patterns in different portions thereof. For 65 example, besides the usual normal and reverse plated pattern extending throughout the stocking, provision may be made for the formation of a clock or the like extending through only 70 a portion of the design. The groups of levers may be selectively rendered operative or inoperative by control of levers 160 which engage their rear ends and pull them away from the tricks on the trick wheel 142 against the action 75 of the springs 161. The levers 160 are independ-

ently controlled by links 162 connected to arms on three of the nested shafts hereafter referred to.

The lowermost cam 62, which is also pivoted at 141, is controlled by a connection through a link 164 to an arm carried by still another of the nested shafts. Cam 51 is carried by a suitable lever link-connected to one of the set of nested shafts heretofore referred to as controlled by the main pattern drums. Normally this cam 10 51 is out of action.

The yarns A and B, which are to be selectively normal and reverse plated, are fed to the needles in conventional fashion, for example, by being fed from yarn fingers 9 located in the throat 15 11 of the usual latch ring. The yarn B which is the normal backing yarn is preferably under greater tension than yarn A. If yarn changes 20 are to be made, yarns carried by the different fingers may be selectively brought into operation at predetermined times by the usual yarn changing mechanism, involving conventional clamping and cutting devices.

The operations involved in producing normal and reverse plating by the mechanism just described will be readily understood from a consideration primarily of Figs. 3 and 4, showing the cam arrangements, together with occasional reference to the other figures, particularly Figs. 2 and 9, in the matter of details of operation 30 of the sinkers.

In Fig. 3 there are indicated in dotted lines the paths of characteristic parts of the various elements associated with the needles in the needle slots and the needles themselves. For example, at a and b there are indicated the alternative paths of the needle butts, at c and d there are indicated the alternative paths of the butts 18 of the jack guides 14, at e and f there are indicated the alternative paths of the shoulders 46 of the lower jacks 42, and at g and h there are indicated alternative paths of the butts 40 of the intermediate jacks 38. It will be noted that through the greater part of a revolution the butts of the needles and intermediate jacks and the shoulders of the lower jacks follow constant paths. The elements associated with the needle cylinder move to the left in Fig. 3 during rotary knitting.

Initially let it be assumed that a particular 50 set of elements associated with one needle and an adjacent sinker are in such position that the upper end of the lower jack is at the position of cam 56. At such time the jack guide 14 of this set of elements may be in either upper or lower position with its butt 18 following either path c or d, depending upon the selection made prior to the previous stitch drawing operation. The intermediate jack 38 will have been lowered 55 and will in turn have lowered the lower jack 42, the lower end of which will have been projected outwardly by cam 56 if it had not previously been in such position. The sinkers on both sides of the needle referred to will be in their inner positions. A jack 20 associated with either 60 of these sinkers will be in one of alternative outer positions depending upon whether or not it is raised or lowered. If it is raised, then it may be in an extreme outer position to which it 65 would have been thrown by centrifugal action if unrestrained by friction. If it is in lower position, the turned end of its arm 23 will have been engaged either centrifugally or due to the 70 action of cam 53 with the annular shoulder 21 of 75

the upper portion of the cylinder. The needle will be in a position, following this lowering by cam 87, corresponding to the portion of the line *a* beyond cam 87. The loop thereon will 5 not have cleared the latch.

As the rotation proceeds, the lower jack will ride upwardly over levelling cam 58 and its butts may or may not be engaged by one of the cams 60. A jack, the lower end of which is 10 rocked inwardly, will, in the next stitch-drawing operation, determine the formation of a normal loop. Assuming that the lower jack under consideration was not acted upon by any of cams 60, its shoulder 46 will remain out in a 15 position to ride up the slope 64 of cam 66 along the upper path *f*. The butt of the intermediate jack will then follow path *h* and as the end of the rise is reached, the corresponding needle will be pushed upwardly so that its butt follows 20 path *b* in position to later engage cam 74. If, on the other hand, a lower jack is pressed inwardly by the action of one or more of cams 60, its shoulder 46 will fail to engage the slope 25 64 of cam 66 and will follow path *e*. The butt of the intermediate jack will then remain at the same level and move along path *g* and the needle butt will move along path *a* underneath cam 74 so that it will not be raised by that cam.

30 In the meantime, the jack 20 will be pushed inwardly by the action of cam 41 and while this jack is held inwardly the butt of jack guide 14 will reach the position of cam 72. If the jack guide is held lowered, it will pass below cam 72 35 without being acted upon thereby. On the other hand, if it is in raised position, it will be lowered by cam 72 with the result that any jack passing this point will occupy the same lower position in which it will be yieldingly retained by 40 the location of the lower of the spring bands 17 above projection 16. The preliminary inward movement imparted to the jack 20 is for the purpose of insuring that the turned end of its arm 23 is inwardly of the shoulder 21 of the 45 needle cylinder so that, if it is associated with a jack guide which is lowered, the turned end will pass downwardly inside the shoulder. If the jack 20 was held in its lower position, it will already have been restrained from outward movement by the engagement of the turned end of its arm 23 with shoulder 21 and will be moved only 50 slightly inwardly by cam 41.

If the needle has been raised as indicated above, it will ride up cam 74 and the loop which 55 it carries will pass below its latch. When it moves along the upper portion of the slope of cam 74, its shoulder will engage and move upwardly the jack guide 14, raising the butt of this guide to the level *d*. Just prior to such rise, 60 cam 25 insures that the jack 20 is sufficiently far out so that if it rises its arm 23 will not jam against the projection 36 on the bottom of the sinker. In general, centrifugal action upon the jacks insures that they occupy outer positions 65 gaging the shoulder 21. Fig. 1 shows the parts in the positions attained as the needle reaches the upper end of cam 74.

Following the selective rise of its jack guide 14, a raised needle will be lowered by cams 76 and 70 78, whereby it is brought to a level with the needles which were not previously raised to pass with the latter over cam 54, which serves to raise the last named needles to a latch-clearing height. Simultaneously, the raised intermediate and lower 75 jacks are moved downwardly by cam 88, any

raised lower jack being previously forced off the cam 66 by the action of the slope 68. Downward overrun of any lower jack is prevented by the cam 70.

Upon reaching cam 45, which only acts during 5 reciprocation, the sinker will already occupy an inner position and consequently will be withdrawn by a portion 171 of cam 43 together with its jack 20 if the latter is in upper position and has not already been thrown out centrifugally 10 to a greater extent. The yarns between the loops carried by the needles which have heretofore been located within the sinker throats below the nibs 31 and will at this time move slightly outwardly, lie, due to the retraction of the sinkers, 15 upon the upper portions of the ledges 32. They continue to occupy such positions as yarns are taken for the formation of new loops.

As the position of cam 82 is reached, the needles will have taken yarns from the feeding fingers. Cam 82 (or one of a plurality of such cams if more than one is used) will project a jack 20 inwardly irrespective of whether it is in upper or lower position by engagement with its butt 83. If it is in upper position, its arm 23 will engage 25 projection 36 of its corresponding sinker and impart to the sinker a premature inward movement so that the yarns are drawn over the edge 33 of the sinker behind its nib 31, thus effecting reverse plating. On the other hand, if the jack 20 30 were in lower position, inward movement imparted to it by cam 82 would not be transferred to the sinker and consequently the yarns would be drawn over the edge 32 of the sinker in front of nib 31 to produce normal plating. Fig. 2 illustrates this action. The sinkers indicated at *n*, 35 *o*, *p* and *q* have passed the location of the cam 82 and have not been moved inward. As a consequence, they will determine the formation of normal plating in their wales. On the other 40 hand, the sinkers *r* and *s* preceding the ones just mentioned have been moved inwardly through the action of cam 82 on jacks 20 and the loops are being drawn over the backs of their nibs to produce reverse plating.

Immediately after the jacks 20 are freed from the active surface of cam 82, the sinker butts are engaged by the cam surface 171 and the sinkers which are determining reverse plating are thereby moved slightly outwardly as indicated at *t* 50 and *u* in Fig. 2.

In accordance with the present invention, the events occurring at this time are precisely related to each other to insure perfect reverse plating confined to single sinker wales. In order to bring 55 out what occurs and how these events are related, reference may be made to Fig. 9 which illustrates the formation of normal plating in the wales of sinkers 200, 204 and 208 and of reverse plating in those of sinkers 202 and 206. In previous 60 sinker reverse plating, the reversals of the yarns have not been confined to the sinker wales but have been uncontrollably extended into the preceding needle wales. If the degree of extension into such wales was controlled, the resulting 65 product would be satisfactory. But even slight variations, unnoticeable at the borders of large reverse plated areas, become very noticeable where reverse plated loops are to stand out individually as in work produced as illustrated in 70 Fig. 9. Unless the reversals are the same in each reverse plated loop, an unsightly fabric results.

It has been found that perfect results depend upon the proper relationship of the needles, 75 yarns and sinkers and movements thereof rela-

tive to each other as the old loops pop over the needle hooks. These critical relationships may be best understood by considering particularly the yarn position diagrams at the right in Fig. 9. 5 (For clarity of illustration, the needle and sinker spacings are exaggerated in this figure.) The yarns at a needle such as 210, the hook of which has not yet engaged them, lie with the untensioned facing yarn A inwardly and below the 10 tensioned backing yarn B. Normally these yarns would retain their relative inner and outer positions as they were drawn over the ledge 32 of a retracted sinker such as 200.

The advanced sinker 202 is illustrated as at a 15 position of first contact of its butt with the retracting cam 171 so that it is at its most inward position. Just as it reaches this point, the yarn A will touch its edge behind the nib, while the following needle 212 will just about engage the 20 yarn B but not A and will not have drawn yarn B downwardly to the level of A. The preceding needle 214, however, will have engaged both 25 yarns and will have drawn them downwardly to such extent as to cause them to engage the ledge 30 32 of the retracted preceding sinker 204. The needle 214 will be in such position that the loop of the preceding course is just about to slip over its hook under the tension of the fabric, while the loop slipping over the hook of needle 216 is in engagement with the yarns in its hook. The cam 171 is provided with such angle that it fully 35 retracts a sinker when the sinker moves through approximately the angular spacing between sinkers.

35 The sinker 206 has been fully retracted by cam 171 to cause the yarn A to be displaced below and outwardly of yarn B and is just about to be projected by knock over cam 47. The needles 216 and 218 by their depressed position and aided by 40 sinkers 204 and 208 hold the yarns in their normal relationship so that the reversal is totally confined to the sinker wale between them. The reversal is aided and maintained by the slipping over of the loops of the preceding course and as 45 a result definite uniform reversal is effected.

It will now be clear why adjustment of cam 171 is so essential for good results. The attainment of the precise relationships just mentioned obviously requires that the sinker retraction 50 must be very accurately adjusted relative to the needle movements, or, more essentially, to the engagements of the yarns with the sinkers. Obviously this varies with the sizes of yarns, and also with the kinds of yarns since reversals of 55 smooth yarns are effected much more readily than reversals of rough, fuzzy yarns and the amount of reversal is therefore dependent on the time of sinker retraction. Loop adjustment by needle cylinder adjustment changes the relationship of the needles and sinkers and, of course, the proper location of cam 171. After 60 all other factors are taken care of the cam 171 is positioned to secure best results.

Comparison of this method of reversal with 65 the usual sinker reversal is worthy of note. In the usual reversal, the reversal is actually caused by a needle to the outside of the hook of which the yarns are carried by sinker retraction. The result is that reversal occurs in both the sinker and needle wales.

It will be clear that when two or more reversing sinkers are adjacent each other both will, of course, produce reversals and reversals will also occur in intermediate needle loops.

70 75 The total drawback effected by cam 171 is not

of particular moment as regards precision of reverse plating but merely takes care of stitch equalization, thus functioning in this respect the same as the fixed cams heretofore provided, to prevent reverse plated loops being tighter than 5 normal plated loops. The drawback varies with different gauges but requires no adjustment in a particular machine. The holding of the reversing sinkers in retracted position insures correction of yarn positions to form normal loops. 10

During the preceding operations, when certain of the sinkers are selectively moved inwardly, the band-holding bits function to hold out the spring band 39 to prevent the premature inward movement of sinkers which are not to be moved 15 inwardly in spite of the fact that the operative edge 177 of the cam 43 is cut away as at 179. As indicated above, a portion 49 of cam 43 continues to act on the longer butts of the band-holding bits to prevent the action of band 39 upon the 20 sinkers, which will be centrifugally urged outwardly.

If a sinker was not prematurely moved inwardly, it will be moved inwardly by the action of the usual cam 47, which serves to produce the 25 inward movement to knock over the old loops.

The needle is now raised by cam 86 in order that the loops drawn behind the sinker nibs may be raised so as to clear the nibs. When this rise takes place, and particularly if the fabric is loose, 30 when the reverse plated loops slip forward they may pull the loops of the previous course out of the sinker throats, with the result that the fabric may get above the sinkers and therefore out of control. To avoid this, the needles are again depressed by a cam 87 immediately following their rise over the end cam 86 and at the same time, by means of the supplementary sinker cam 190, the sinkers are backed away from the needles as they descend and are then again moved inwardly by 40 the spring band as the needles reach their low point to cause the throats of the sinkers to re-engage any loops which may have been previously lost. Since this action is only necessary when reverse plating is being effected and loops are 45 being drawn behind the sinker nibs, provision is made, as described above and as indicated in Fig. 4, to cause both the cams 87 and 190 to remain inoperative unless reverse plating is being done.

Further details of the operation, particularly 50 as regards the operation of the machine when no reverse plating is being accomplished, are given in the Harold E. Houseman application referred to above. Since the present invention is not concerned with such operations, they are not described herein in detail. It is sufficient to remark that the withdrawal of cams 87 and 190 from operation during reciprocation prevents their interference with the formation of heels and toes.

By reason of the provision of the adjustable re- 60 tracting cam 171, perfectly clean-cut patterns may be produced even when the full capabilities of the pattern mechanism described herein are used. It is possible by the use of the present mechanism to produce clean patterns involving 65 alternative reversals of the yarn positions in successive wales. It will be clear that adjustment of a retracting cam such as 171 may be effected in other fashions than that specifically shown herein.

70 75 What I claim and desire to protect by Letters Patent is:

1. A circular knitting machine including a needle cylinder, needles slidable in the cylinder, means for feeding a plurality of yarns to the 75

needles, sinkers equipped with nibs movable between the needles and cooperating therewith in the formation of stitches, means for normally advancing sinkers to cause loops to be drawn in front of their nibs, means for prematurely advancing certain sinkers to cause loops to be drawn behind their nibs, and an adjustable cam for retracting each of said last named sinkers when the needle preceding said sinker is passing below the fabric level to draw a new loop through one previously made.

2. A circular knitting machine including a needle cylinder, needles slideable in the cylinder, means for feeding a plurality of yarns to the needles, sinkers equipped with nibs movable between the needles and cooperating therewith in the formation of stitches, means for normally advancing sinkers to cause loops to be drawn in front of their nibs, means for prematurely advancing certain sinkers to cause loops to be drawn behind their nibs, and an adjustable cam for retracting each of said last named sinkers when the needle preceding said sinker is passing below the fabric level to draw a new loop through one previously made, said cam being adjustable to compensate for a change of position of said fabric due to vertical adjustment of the needle cylinder.

3. A circular knitting machine including a needle cylinder, needles slideable in the cylinder, means for feeding a plurality of yarns to the needles, sinkers equipped with nibs movable between the needles and cooperating therewith in the formation of stitches, means for normally advancing sinkers to cause loops to be drawn in front of their nibs, means for prematurely advancing certain sinkers to cause loops to be drawn behind their nibs, and an adjustable cam for retracting each of said last named sinkers when the yarns in the needle preceding it are being drawn through the loop on said needle and are being turned by said loop as it slips over the needle hook.

4. A circular knitting machine including a needle cylinder, needles slideable in said cylinder, means for feeding a plurality of yarns to the needles, members movable between the needles and arranged to engage the yarns when stitches are being drawn, said members having nibs movable between the needles, means for selectively controlling movements of said members to cause loops to be drawn in front of said nibs to produce normally plated loops and behind said nibs to produce reverse plated loops, and additional means acting immediately after loops have been formed to locate the reverse plated loops in front of said nibs.

5. A circular knitting machine including a needle cylinder, needles slideable in said cylinder, means for feeding a plurality of yarns to the needles, sinkers movable between the needles and arranged to engage the yarns when stitches are being drawn, said sinkers having nibs movable between the needles and providing throats for the reception of loops, means for selectively controlling movements of said sinkers to cause loops to be drawn in front of said nibs and into the throat to produce normal plated loops and behind said nibs to produce reverse plated loops, and additional means acting immediately after loops have been formed to locate the reverse plated loops in the sinker throats, so that they will be under control of the sinkers and will be cast off in the next course of knitting.

6. A circular knitting machine including a needle cylinder, needles slideable in said cylinder, means for feeding a plurality of yarns to the nee-

dles, sinkers movable between the needles and arranged to engage the yarns when stitches are being drawn, said sinkers having nibs movable between the needles and providing throats for the reception of loops, means for selectively controlling movements of said sinkers to cause loops to be drawn in front of said nibs and into the throat to produce normal plated loops or behind said nibs to produce reverse plated loops, and means for locating the reverse plated loops in the sinker throats comprising a cam for retracting the sinkers and a cam for lowering the needles while said sinkers are retracted to draw the loops below their nibs.

7. A circular knitting machine including a needle cylinder, needles slideable in said cylinder, means for feeding a plurality of yarns to the needles, sinkers movable between the needles and arranged to engage the yarns when stitches are being drawn, said sinkers having nibs movable between the needles and providing throats for the reception of loops, means for selectively controlling movements of said sinkers to cause loops to be drawn in front of said nibs and into the throat to produce normal plated loops or behind said nibs to produce reversed plated loops, means for locating the reverse plated loops in the sinker throats comprising a cam for retracting the sinkers and a cam for lowering the needles while said sinkers are retracted to draw the loops below their nibs, and means whereby said sinker retracting cam and said needle lowering cam are rendered active only when reverse plating is taking place.

8. The method of effecting reverse plating on a knitting machine provided with independently movable needles and sinkers, the sinkers being provided with nibs having sloping backs, comprising feeding a plurality of yarns to the needles, normally advancing certain sinkers to cause loops to be drawn in front of their nibs, prematurely advancing certain sinkers to cause loops to be drawn on the sloping backs of their nibs, and retracting each of said last named sinkers when the needle preceding said sinker is passing below the fabric level to draw a new loop through one previously made.

9. The method of effecting reverse plating on a knitting machine provided with independently movable needles and sinkers, the sinkers being provided with nibs having sloping backs, comprising feeding a plurality of yarns to the needles, normally advancing certain sinkers to cause loops to be drawn in front of their nibs, prematurely advancing certain sinkers to cause loops to be drawn on the sloping backs of their nibs, and retracting each of said last named sinkers when the yarns in the needle preceding it are being drawn through the loop on said needle and are being turned by said loop as it slips over the needle hook.

10. The method of effecting reverse plating on a knitting machine provided with independently movable needles and sinkers, the sinkers being provided with nibs having sloping backs, comprising feeding a plurality of yarns to the needles, normally advancing certain sinkers to cause loops to be drawn in front of their nibs, prematurely advancing certain sinkers to cause loops to be drawn on the sloping backs of their nibs, and retracting each of said last named sinkers when the needle preceding said sinker is passing below the fabric level to draw a new loop through one previously made, so timing the retraction of said reversing sinker that reverse plating will

be confined to the wale formed by said sinker when the sinkers on either side of it are being projected normally to effect regular plating.

11. The method of effecting reverse plating on
5 a knitting machine provided with independently
movable needles and sinkers, the sinkers being
provided with nibs having sloping backs, com-
prising feeding a plurality of yarns to the needles,
normally advancing certain sinkers to cause loops
10 to be drawn in front of their nibs, prematurely
advancing certain sinkers to cause loops to be

drawn on the sloping backs of their nibs, and
retracting each of said last named sinkers when
the yarns in the needle preceding it are being
drawn through the loop on said needle and are
being turned by said loop as it slips over the 5
needle hook, so timing the retraction of said re-
versing sinker that reverse plating will be con-
fined to the wale formed by said sinker when the
sinkers on either side of it are being projected
normally to effect regular plating. 10

PAUL W. BRISTOW.
